UNITED STATES PATENT OFFICE.

PARIS J. RIDDELL, OF NEW YORK, N. Y., ASSIGNOR TO THE BRUNSWICK-BALKE-COLLENDER COMPANY, A CORPORATION OF OHIO.

BOWLING-ALLEY BALL-GUTTER.

No. 804,551.

Specification of Letters Patent.

Patented Nov. 14, 1905.

Application filed April 24, 1905. Serial No. 257,048.

To all whom it may concern:

Be it known that I, PARIS J. RIDDELL, a citizen of the United States, residing in New York city, borough of Brooklyn, county of Kings, and State of New York, have invented a new and useful Improvement in Bowling-Alley Ball-Gutters, of which the following is a specification, reference being had to the accompanying drawing, forming part thereof.

With reference to the construction of the ball-gutters of a "regulation" alley the rules of the congress prescribing only a certain width for the gutter and a certain descent of the pit end portion thereof it has been customary for a good while (until very lately) for alley-builders to make the ball-gutters otherwise (as to the measurement, &c.) as prescribed by the congress concave in cross-sectional shape during the entire length of the gutter—*i. e.*, from the players' end to the extreme pit end of the gutter. In view, however, of a certain known function or operation of this dishing or concave ball-gutter (which has been and is universally known as the "cove" gutter invented and patented by one W. H. Wiggins) conducive to the making of larger scores by the players than attainable with the use of the old-fashioned previously-used "flat" ball-gutters, the American Bowling Congress on or about February 25, 1905, (at its annual meeting at Milwaukee) passed or established a new regulation with reference to the construction of all ball-gutters, which requires them to have that pit end portion which is contiguous to the "pin-platform" of the alley-bed made flat-bottomed or polygonal in cross-sectional shape, after the fashion of the very old-fashioned ball-gutters, instead of after the fashion of the cove, which for some years prior to the present time had been almost universally used. As made prior to my invention, this flat-bottom portion of the ball-gutter has been constructed in about the same manner as gutters having flat bottoms throughout their whole length were built prior to the supplanting of them by the cove—that is to say, the portion of the gutter required since the new congress law to be flat-bottomed has been made with a simple bottom board extending widthwise from the vertical side or edge of the bed to the vertical side or wall (nine inches distant from the bed) of the division-strip or "stringer-beam" of the alley, the said bottom (in one or two

pieces) being nailed down to the foundational stock of the alley structure and with the usual quarter-round fillets or molding-strips nailed into each corner of the gutter—*i. e.*, each right angle formed by the junction of the horizontal gutter-bottom with the vertical sides of the walls, respectively, of the bed and division-strip. In practice it has been found that under this mode of construction these parts of the bottom and also the quarter-round molding-strips are often either split by the nailing-in process or subsequently to the building of the alley (without any splitting of these parts) become split, so that the nail-heads are exposed and inflict injury on the superficies of the (expensive) tenpin-balls. Furthermore, it has been found that under this method of construction this flat-bottomed portion of the ball-gutter does not possess the desired durability, but soon becomes structurally impaired and inoperative. I propose by my improvement to render this portion of the ball-gutter, as it now has to be made as to cross-sectional shape, more durable and desirable in every way, while at the same time making the whole alley structure better than heretofore so far as is concerned the pit end portion thereof.

To these ends and objects my invention may be said to consist, essentially, in a pit end portion ball-gutter construction in which the members of the flat bottom, the corner-filling, quarter-round molding-strips, the alley-bed edge, and the division-strip are all firmly and lastingly united to each other and the gutter-bottom to the foundation of the alley, and without any nailing together of any of the parts, all as will be hereinafter more fully described and as will be most particularly pointed out in the claims of this specification.

To enable those skilled in the art to practice my invention, I will proceed to more fully describe my improved construction, referring by letters to the accompanying drawing, which forms part of this specification, and in which I have shown my invention carried out in the precise form in which I have so far practiced it.

In the drawing I have shown in vertical cross-section my improved ball-gutter pit end portion.

A is part of the usual alley-bed, and B the division-strip or stringer-beam with the in-

termediate ball-gutter C, made according to my invention.

I have made the drawing to a scale of three-quarters the size of a regulation alley and have marked thereon the measurements of the full-sized working structure.

As clearly illustrated, the flat bottom of the gutter is composed of two boards or pieces c c, each about one and one-eighth of an inch 10 in thickness and equal in width to one-half the width of the gutter—i. e., one-half the distance between the edge of the bed A and the vertical face of the division-strip B. These bottom pieces c c are securely fastened down 15 to the foundational timbers of the alley structure at the vicinities of their meeting edges (and at points properly distant apart lengthwise of the gutter) by wood-screws, as clearly shown, the heads of which are sufficiently 20 countersunk into the wooden stock of strips c c to permit the insertion within said stock of wooden covering-disks f, which preferably are glued in place and which being finished off at their exposed surfaces flush with the 25 top surfaces of boards c c do not in the least impair the perfectly plane and smooth top surface of the gutter-bottom.

D D are two quarter-round molding-strips arranged, as usual, in the corners or angles 30 formed by the junctions of the bottom boards c c with, respectively, the alley-bed edge and the division-strip; but instead of being made as usual prior to my invention and fastened in place as previously each of these corner- 35 filling strips D is made, as seen, with a downwardly-projecting tongue e, that fits into a longitudinal groove in the bottom board c of the gutter and is securely fastened in place, one to the alley-bed A, and the other 40 to the stringer-beam B by wood-screws g, the heads of which screws are countersunk into the wood of strips D sufficiently to permit the perfect covering over of said heads with inserted and (preferably) glued-in 45 wooden filler-disks i. These quarter-round molding-strips D, tongued and grooved with the bottom board c, are securely glued in position, and after the securement of the united 50 parts to the bed edge and division-strip, respectively, the result is a concrete bowling-alley-ball-gutter structure, which while it meets fully the requirements of the latest bowling congress law or regulation is made more durable and in every way more desirable

in actual practice than anything made in accordance with the present regulation prior to my invention.

In the improved construction shown and described there never can be any exposed or worked-loose heads of nails, (or other metallic fasteners,) which operate to scratch and mar the surfaces of the balls rolling in the gutters, the corner molding-strips can never shrink away from or become in the least separated from either the horizontal (bottom 65 board) or the vertical surfaces of the alley structure, and the concrete alley structure comprising the bed edge, the division-strip, and the intermediate ball-gutter pieces is perfectly strong and durable.

Having now so fully described my improved construction that those skilled in the art can easily practice my invention, what I claim as new, and desire to secure by Letters Patent, is—

1. In a bowling-alley, a flat-bottomed ball-gutter portion composed of bottom boards securely fastened to the foundational portion of the alley structure; and corner filling-strips or moldings glued in place; the said bottom 80 boards and filler-molding being permanently secured in place by means of wood-screws, with countersunk and wood-covered heads; all substantially as and for the purposes set forth.

2. In a bowling-alley, the combination, with the alley-bed, and the division-strip, of a flat-bottom ball-gutter composed of bottom boards that are grooved longitudinally; and corner filling-strips that are tongued into the 90 said grooves of said bottom boards; the gutter parts being securely fastened together, and to the said bed and division-strip; all as and for the purposes set forth.

3. In a bowling-alley the combination with 95 the bed and division-strip of a flat-bottom ball-gutter composed of grooved bottom boards, and tongued corner filling-strips; the said tongued and grooved parts being securely glued together and all the parts fastened in 100 place by wood-screws, substantially as set forth.

In witness whereof I have hereunto set my hand this 18th day of April, 1905.

P. J. RIDDELL.

In presence of—

JOHN C. MCKENZIE,
DANIEL F. DALY.
